[57] CLAIM

The ornamental design for a t shirt compressed in the shape of a spacecraft, as shown and described.

DESCRIPTION

FIG. 1 is a front plane view of the t shirt compressed in the space of a spacecraft, the rear plane view being a mirror image of the front plane view and not shown;

FIG. 2 is a top view of said t shirt compressed in the shape of a spacecraft;

FIG. 3 is a right side view of said t shirt compressed in the space of a spacecraft, the left side view being a mirror image of the right side view and not shown; and,

FIG. 4 is a bottom plane view of the t shirt compressed in the space of a spacecraft.
